UNITED STATES PATENT OFFICE.

CHARLES A. NEEDHAM, OF NEW YORK, N. Y., ASSIGNOR OF ONE-HALF TO
GEORGE G. NEEDHAM, OF NEW YORK, N. Y.

AMUSEMENT DEVICE.

SPECIFICATION forming part of Letters Patent No. 746,986, dated December 15, 1903.

Application filed March 4, 1903. Serial No. 146,253. (No model.)

To all whom it may concern:

Be it known that I, CHARLES A. NEEDHAM, a citizen of the United States, and a resident of the borough of Manhattan, in the city and State of New York, have invented a new and useful Improvement in Amusement Devices, of which the following is a specification.

My invention relates to an improvement in amusement devices, and has for its object to provide an amusement device comprising a way or track—such, for instance, as a wire or string, which carries a boat provided with sails for propelling the boat along the said way or track.

15 A further object is to provide a device of the above character in which the sails may be automatically reversed when the boat reaches a predetermined point on the way or track for permitting the sails to propel the boat in the opposite direction, thus causing the boat to traverse the way or track back and forth automatically as long as there is sufficient wind to cause the sails to move the boat.

20 25 A further object is to provide a device of the above character which will be very simple and will not be liable to become disarranged by rough usage.

A practical embodiment of my invention is 30 represented in the accompanying drawings, in which—

Figure 1 represents the amusement device in side elevation, the boat being shown in full lines headed in one direction and in 35 dotted lines headed in the opposite direction after the sails have been reversed by the engagement of the reversing device by the stop carried by the way or track. Fig. 2 is a transverse horizontal section in the plane of the 40 line A A of Fig. 1. Fig. 3 is an enlarged end view of the boat with the mast broken away and the sails removed. Fig. 4 is a view in side elevation of a modified form. Fig. 5 is an end view of the same, the mast being 45 broken away and the sails removed. Fig. 6 is a side view of a third form of my invention; and Fig. 7 is an end view of the same, the mast being broken away and the sails removed.

50 The way or track is denoted by 1, and it

may consist of a wire, cord, or other suitable suspension device drawn taut between two suitable supports 2 and 3.

In the form shown in Figs. 1, 2, and 3 the hull or body of the boat is denoted by 4, and is preferably sharpened at both ends to permit the boat to be moved in both directions along its way or track without appearing to be moving rearwardly. A mast 5 uprises from the hull 4 of the boat, which mast is 55 mounted to rock on its own axis. The foot of the mast is stepped in the hull of the boat and a bracket 6 uprises from the deck and supports the mast a short distance above the same. In the present instance I have shown 60 the mast as carrying a mainsail 7 and jib 8. A platform 9 is fixed to rock with the mast 5 and is located just above the bracket 6. The mainsail-sheet 10 is adjustably secured to the rearwardly-projecting portion of the platform 9 and the foot of the jib-stay 11 is secured to the forwardly-projecting portion of the said platform. The jib-sheet 12 is also adjustably secured to the said platform 9. By this means I am enabled to adjust the 65 sails of the boat to the proper position to permit the wind to propel the boat along the way or track to the best advantage.

The way or track 1 is located in a longitudinal groove 13, which opens through the 80 keel of the boat, and the said keel of the boat is provided with counterbalance-weights 14, which tend to keep the boat at all times in a vertical position upon the way or track.

The means which I have shown for reversing the sails when the boat reaches a predetermined point on the way or track is constructed, arranged, and operated as follows: A longitudinally-sliding bar 15 is mounted on the boat 4 to slide in suitable guides 22 85 23, and a flexible connection 16 is passed around the mast and has its opposite ends secured to the bar 15, as shown at 17 18. The bar 15 is so arranged that it will project a slight distance beyond the forward end of the 90 boat when the boat is being propelled in one direction, so that the said forwardly-projecting end of the bar will be engaged by one of the supports 2 or 3 of the way or track and forced rearwardly. This rearward move- 95 100

ment of the bar will rock the mast 5 and platform 9 a half-revolution, thus reversing the sails and permitting the wind to drive the boat in the opposite direction.

5 In the forms shown in Figs. 4 and 5 the groove 19 for receiving the way or track 1 opens through the side of the hull, and in this form it is intended to manually remove the boat from the way or track and reverse 10 it to cause the boat to be propelled in the opposite direction.

In the form shown in Figs. 6 and 7 I have shown the boat as supported by the way or track by means of suspension-hooks 20 projecting upwardly from the deck, a hook bracket or step 21 also being provided for the mast 5, so that the way or track may run longitudinally along the middle of the boat, so that the boat is equally balanced on the 20 way or track. In this form also it is intended that the boat should be manually removed from the way or track when it reaches a predetermined point and reversed for permitting it to be driven in the opposite direction.

25 The amusement device constructed and arranged as above set forth is extremely simple and strong and is one in which the sails may be adjusted so as to obtain the best effect from the wind-pressure.

30 It is to be understood that the supports 2 and 3 of the way or track may be of any suitable form.

35 It is evident that changes might be resorted to in the form, construction, and arrangement of the several parts without departing from the spirit and scope of my invention. Hence I do not wish to limit myself strictly to the structure herein set forth; but

What I claim is—

40 1. An amusement device comprising a way or track and a boat removably supported

thereby, said boat being provided with sails for propelling it along the way or track.

2. An amusement device comprising a way or track, and a boat having a longitudinal 45 groove therein, for receiving the way or track for supporting the boat, said boat having sails for propelling it along the way or track.

3. An amusement device comprising a way or track and a boat having a longitudinal 50 groove therethrough, opening to the exterior of the boat for removably receiving the way or track therein, the said boat having sails for propelling it along the way or track.

4. An amusement device comprising a way 55 or track and a boat having a longitudinal groove therethrough for receiving the way or track, a mast and sails surmounting the boat for propelling it along the way or track and a counterbalance-weight carried by the boat 60 below the groove for normally holding the boat in a vertical position on the way or track.

5. An amusement device comprising a way or track, a boat supported thereby, a mast supported to rock in suitable bearings carried 65 by the boat, sails carried by the mast and a supplemental platform to which the sails are attached fitted to rock with the mast, a reversing device carried by the boat and means for operating the reversing device when the 70 boat reaches a predetermined point on the way or track for permitting the sails to propel the boat in the opposite direction.

In testimony that I claim the foregoing as my invention I have signed my name, in presence of two witnesses, this 19th day of February, 1903.

CHARLES A. NEEDHAM.
